UNITED STATES PATENT OFFICE.

CHARLES E. HEYER, OF CHICAGO, ILLINOIS, ASSIGNOR TO BARNHART
BROTHERS & SPINDLER, OF SAME PLACE.

DESIGN FOR A FONT OF PRINTING-TYPE.

SPECIFICATION forming part of Design No. 20,749, dated May 19, 1891.

Application filed April 14, 1891. Serial No. 388,948. Term of patent 14 years.

To all whom it may concern:

Be it known that I, CHARLES E. HEYER, a citizen of the United States, residing at Chicago, county of Cook, and State of Illinois, have invented and produced a new and original Design for a Font of Printing-Type, set forth in the following specification, reference being had to the accompanying typographical impressions, forming a part thereof.

10 This design comprises capitals and lower-case letters, figures, dollar-mark, and character &.

The letters and characters are moderately condensed, devoid of shades, formed of medium-weight lines of uniform width in the upper and lower case letters, respectively, with the following exception: in lower-case letters which in standard script have full-length loop above the line—viz., b f h k l—

20 have in this design as an ornamental finish at the top of a full-length straight upright stem a short light loop turned on the right-hand side. The letters g and y have their tails below the line formed of a curve slightly lighter than the body-lines, approximately 25 parallel with the lower curve of the body and very near thereto, but below the line. Lower-case f has its characteristic consisting of a short horizontal stroke jutting off to the right 30 from the stem. The "cross" of t is precisely similar, so that it does not cross the stem,

and the lower terminal of t is also a similar horizontal stroke on the line. Capital C has no characteristic, but consists of a simple arc of less than one hundred and eighty degrees, 35 open to the right, the two extremes pointing divergently; and capital G is formed of a precisely similar open arc, to whose lower extremity there is added a vertical half-stem, which has for the characteristic at the upper 40 end an inwardly-projecting horizontal short stroke. Both upper and lower case v have their oblique lines connected by a short horizontal stroke resting on the line. Capital N has its oblique stroke joined to the final up-right stem some distance above the line, although it joins the initial upright stroke at the top. All letters and characters are wholly devoid of ceriphs or analogous terminals or ornamentations. 45 50

I claim—

The design for a font of type herein shown and described.

In testimony whereof I have hereunto set my hand, at Chicago, Illinois, in the presence 55 of two witnesses, this 8th day of April, A. D. 1891.

CHARLES E. HEYER.
